(57) **CLAIM**

The ornamental design for a thermistor sensor probe, as shown and described.

DESCRIPTION

FIG. 1 is a front perspective view of a thermistor sensor probe constructed in accordance with the new design;

FIG. 2 is a top view thereof;

FIG. 3 is front view thereof (the back being identical); and,

FIG. 4 is a side view thereof (the opposite side being identical).

It should be further understood that the broken lines showing in Figures are for illustrative purposes only, and form no part of the subject invention.
